UNITED STATES PATENT OFFICE

164,470

SPOON OR SIMILAR ARTICLE OF FLATWARE

Norman Bel Geddes, New York, N. Y., assignor to
National Silver Company, New York, N. Y., a
corporation of New York

Application May 25, 1951, Serial No. 15,319

Term of patent 14 years

(Cl. D54—12)

To all whom it may concern:

Be it known, that I, Norman Bel Geddes, a citizen of the United States, residing in the city, county, and State of New York, have invented a new, original, and ornamental Design for a Spoon or Similar Article of Flatware, of which the following is a specification, reference being had to the accompanying drawing, forming a part thereof, in which:

Fig. 1 is a front elevational view of a spoon or similar article of flatware, showing the essential features of my new design in full lines.

Fig. 2 is a central longitudinal section taken on line 2—2 of Fig. 1.

Fig. 3 is a transverse section taken on line 3—3 of Fig. 1.

I claim:

The ornamental design for a spoon or similar article of flatware, as shown and described.

NORMAN BEL GEDDES.
